ARCH TYPE LOOSE-LEAF BINDER

Charles C. Rea, Poland, Ohio

Application July 23, 1946, Serial No. 685,667

2 Claims. (Cl. 129—11)

1

This invention relates to a loose leaf binder and more particularly to a form of loose leaf binder known commercially as an arch type.

The principal object of the invention is the provision of an improved arch type loose leaf binder incorporating manually operable means for opening and closing the said binder.

A further object of the invention is the provision of an arch type loose leaf binder incorporating a pair of partially arched members for engaging punched openings in loose leaf forms and means for mechanically moving the said partially arched members into and out of engagement with fixed members so as to open and close the arches thus formed.

A still further object of the invention is the provision of an arch type loose leaf binder mechanism including a pivoted handle and roller member for imparting manual movement to a movably positioned portion of the arch sections of the said binder.

The arch type loose leaf binder shown and described herein has been designed to form a simple and efficient manually operable device for opening and closing the arch members of the loose leaf binder so as to facilitate the positioning thereon or removal therefrom of various punched paper forms.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein—

Figure 1 is a top plan view of the arch type loose leaf binder.

Figure 2 is a front elevation of the arch type loose leaf binder with parts in cross section.

Figure 3 is a side elevation of the arch type loose leaf binder.

By referring to the drawings and Figures 1, 2 and 3 in particular, it will be seen that the arch type loose leaf binder consists of a mounting plate 10 upon which a pair of vertically standing rods 11 are positioned in spaced relationship and that the uppermost ends of these rods 11 are rounded, as indicated in Figure 3 by the numeral 12.

It will also be seen that a pair of partially arch shaped members 13 are formed of a single length of wire-like material, each of the partially

2

arch shaped members 13 standing vertically. Their outermost, downturned ends are indicated by the number 14 in Figure 3 and are cupped to engage the rounded upper ends 12 of the pair of vertically standing members 11. It will thus be seen that the partially arch shaped members 13 and the upstanding members 11, in closed position as illustrated in the drawings, form a pair of complete arches which are useful in holding punched paper forms in loose leaf relation.

In order that the punched paper forms may be positioned on the pair of arches or removed therefrom, the single wire-like member from which the two partial arch shapes are formed is pivoted on the base 10 by means of a pair of straps 15 which in turn are riveted as by means of rivets 16 to the mounting plate 10. The wire shape from which the two partial arch shapes 13 are formed is shaped at a right angle to the normally vertical sections of the partial arches 13 and passes beneath the straps 15 in axial alignment, as best shown in Figures 1 and 3 of the drawings, so that it may be turned while in such axial alignment with the straps 15 and thereby cause the upper portions of the partial arch sections 13 to engage and disengage the upper ends of the vertically standing members 11 and cause the opening and closing of the arch binder.

In order that the opening and closing movement may be effectively imparted to the partial arch sections 13, a section of the wire shape from which they are formed and which section lies between the strap members 15, is shaped so as to lie inwardly and upwardly. This section is generally indicated in the drawings by the number 17. One portion of this inwardly and upwardly extending central section of the wire shape from which the partial arches 13 are formed, is formed in an arc 18, as viewed from the top as in Figure 1, and also in a semi-M shape, as viewed from the end and as shown in Figure 3, thus forming a pair of oppositely inclined sections 19 which are also formed in the arc, as indicated by the numeral 18 in the top plan view of Figure 1. These oppositely inclined sections 19 are spaced apart by a centrally located depressed area 20, when viewed in end elevation, as shown in Figure 3.

In order that this conformation of the wire shape may be employed for imparting movement to the partially arched sections 13, a manually operable lever 21 is pivoted on an elevated support 22 by means of a pivot 23 and has a handle portion 24 extending outwardly to one side of the mounting plate 10. The innermost end of

the lever 21 is provided with a wheel-like roller 25 which travels in an arc based on the pivot 23 when the handle 24 is moved to move the lever 21. The arc traveled by the wheel-like roller 25 conforms exactly with the arc 18 of the wire shape 17 and thereby causes the partial arch members 13 to move into engagement with the upstanding members 11 when the wheel-like roller 25 rests in the depression 29 on the effective apex of the two inclines 19 formed in the wire shape 17.

In order that the moving of the handle 24 forwardly or backwardly will cause the partial arch sections 13 to open with respect to the upper ends of the upstanding members 11, a leaf spring 26 is positioned on the mounting plate 10 and normally urges the wire shape 17 upwardly against the wheel-like roller 25 on the lever 21. Thus, when the wheel-like roller 25 is moved by the lever 21, along the arc 18 and down either one of the inclines 19 of the wire shape, the motion of the spring 26 moves the innermost end of the wire shape 17 upwardly and hence causes the partial arch sections 13 to open with respect to the upper ends 12 of the upstanding members 11. Moving the handle 24 in a reverse motion will also cause the wheel-like roller 25 to roll up either one of the inclines 19 and seat it in the depression 29 and thereby depress the wire shape 17 and thus cause the partial arch portions 13 to close against the upper ends 12 of the upstanding members 11. The arch type loose leaf binder is thereby simply and efficiently operated by one hand of the user, thereby enabling the other hand to be used in placing loose leaf papers in the arch binder or remove them therefrom.

It will thus be seen that the device is simply and efficiently formed and that it will operate effectively with little wear or mechanical difficulty, and that it may be relatively inexpensively formed and hence widely distributed. It will also be seen that the manual motion necessary is on a horizontal plane which readily enables the operator of the arch type loose leaf binder to effect the motion necessary without interference of the desk or table surface upon which the 45 binder is positioned.

Having thus described my invention, what I claim is:

1. An arch type loose leaf binder including a base member, a pair of vertically standing members thereon and a member movably positioned thereon and forming two partial arch shaped members for engaging the said vertically standing members to complete two separate arches, a portion of the said member forming the partial arches being shaped into oppositely inclined sections spaced by a slight depression at the apex of the said inclines, a lever pivoted to the said base member, a roller carried on the said lever and engaging the said inclined sections and spring means normally urging the said inclined sections of the member forming the partial arches against the said roller.

2. An arch type loose leaf binder including a base member, a pair of vertically standing members thereon and a member movably positioned thereon and forming two partial arch shaped members for engaging the said vertically standing members to complete two separate arches, a portion of the said member forming the partial arches being shaped into oppositely inclined sections spaced by a slight depression at the apex of the said inclines, a lever pivoted to the said base member, a roller carried on the said lever and engaging the said inclined sections and spring means normally urging the said inclined sections of the member forming the partial arches against the said roller, the said inclined sections being formed in an arc to conform to the radius of the pivoted lever and roller.
